UNITED STATES PATENT OFFICE.

WILLIAM B. TUNSTALL, OF WORCESTER, MASSACHUSETTS, ASSIGNOR TO SIMPLEX
PLAYER ACTION COMPANY, OF WORCESTER, MASSACHUSETTS, A CORPORATION OF
MASSACHUSETTS.

LYRE AND PEDAL MECHANISM FOR GRAND PIANOS.

Application filed January 24, 1923. Serial No. 614,600.

To all whom it may concern:

Be it known that I, WILLIAM B. TUNSTALL, a citizen of the United States, and a resident of the city of Worcester, county of 5 Worcester, and State of Massachusetts, have invented a new and useful Improvement in Lyre and Pedal Mechanism for Grand Pianos, of which the following is a specification.

10 One object of my invention is to provide a grand piano with a detachable unit including the pedals so that the unit and pedals may be removed and replaced without adjustments or alterations; a further object 15 is to provide such a unit which will not interfere with any player mechanism that may be used under the keyboard and a third object is to provide a rigid and slightly but partly concealed structure connecting the 20 pedals and piano mechanism. These and other objects are accomplished by my invention, one embodiment of which is herein-after more particularly set forth.

For a more detailed description of my invention, reference is to be had to the accompanying drawings, forming a part hereof, in which—

Figure 1 is a side elevation of a grand piano provided with my improvement, parts 30 being broken away to reveal the structure.

Figure 2 is a front elevation of the detachable unit.

Figure 3 is a side elevation of this unit.

Throughout the various views of the 35 drawings, similar reference characters designate similar parts.

A grand piano 1 may be provided in the conventional way with a player action in a drawer 2, supported under the keyboard in 40 a conventional manner. This piano may be supported by the usual legs 3 in the customary way.

The pedal unit 4 is attached to any suitable part of the frame 5 of this piano by 45 means of angle brackets 6 each of which has an upper web 7, a vertical web 8 and a lower web 9 from which is hung a crossing 10 with depending legs 11 which are united at their bottom by the usual fulcrum block 12 which 50 is slotted to carry the usual pedals, such as the sustaining pedal 13, the sostenuto pedal 14 and the shifting pedal 15. All these pedals

are fulcrumed in the usual way and carry at their rear ends the usual wires 16 through which they function.

As the piano mechanism for each of these 55 pedals is the usual mechanism and all are connected to the piano mechanism by the novel, identical, bent levers which will now be described, for convenience, in Figure 1 60 only the connection for the sustaining pedal 12 is shown, it being understood that the other pedals are connected in a corresponding manner.

Each wire 16 runs to a bent lever 17 which 65 is fulcrumed at 18 on a bar that runs from one bracket 6 to the other. Each lever 17 has a horizontal extending arm 19 which is connected to a wire 16 and an upwardly extending arm 20 which is provided with a 70 face 21 near its upper end which engages a corresponding face 22 on an upwardly extending bent lever 23 fulcrumed at 24 and this fulcrum is secured to the frame 5 of a piano in any suitable way. The bent lever 75 23 has an upper arm 25 which is connected to the piano mechanism in any suitable way. In the embodiment shown in Figure 1, this arm 25 is shown connected to a dowel 26 which has its end bushed into the parts it 80 connects, its lower end resting in the arm 25 and its upper end connected into the rail 27 which is pivoted in the usual manner and supports the dampers 28 in the conventional manner. The upper ends of these dampers 85 rest on the strings 29 of the piano.

Other mechanism is connected to the other 90 levers 17 for the sostenuto pedal and the keyboard shifting pedal through suitable bent levers 23, all of which is of the conventional kind and operate in the conventional manner.

From the foregoing, it is apparent that 95 there are three bent levers 17 and three bent levers 23, each lever 17 having a bent lever 23 cooperating therewith and that the levers 23 are pivoted from the piano frame and the levers 17 are pivoted from the unit, to which the pedals are attached. When this unit is placed in position, the surfaces 21 and 22, 100 on the respective bent levers, rub together in proper relation so that when the unit is secured to the frame 5, no adjustments are required and there is no lost motion and

when the unit is removed from the piano, the surfaces 21 and 22 slide apart without interference one with the other. From this it is apparent that this embodiment of my invention obtains the advantages and objects above set forth.

While I have shown and described one embodiment of my invention, it is obvious that it is not restricted thereto, but that it is broad enough to cover all structures that come within the scope of the annexed claims.

Having thus described my invention, what I claim is:

- 15 1. A piano with a pedal and an action and means for connecting this pedal and this action of the piano consisting of bent levers with interengaging parts, one of said levers being connected to said pedal and one of said levers being connected to said action.
- 20 2. A piano with pedals and means for connecting the pedals and piano action embodying a pair of bent levers and an angle bracket, one of said levers being pivoted to the piano and one to said angle bracket.
- 25 3. A piano provided with a pedal unit, the piano having a depending lever and the pedal unit having a bent lever arranged to press against the depending lever of the piano, the unit being provided with an angle

bracket by means of which it may be secured to the piano.

4. A piano with a pedal unit secured thereto, the piano having a depending lever connected to the piano action and the pedal unit having at its top an angle bracket with a bent lever pivoted thereto and engaging the depending lever, the bracket being shaped so that when the pedal unit is in place it is offset towards the front of the piano and space is made for a drawer containing an action.

5. In a pedal unit for grand pianos, a pair of offset brackets supporting a lyre, a connecting rod joining said brackets, bent levers fulcrumed on said rod, said levers operatively connecting the pedals and the piano devices.

6. In a lyre pedal mechanism for player grand pianos, a lyre frame containing pedals and connecting wires, offset brackets from which said lyre frame may be suspended from a piano, bent levers mounted on a common fulcrum carried by said brackets and adapted to engage operating means carried by a piano.

In testimony whereof, I have hereunto set my hand this 20th day of January, 1923.

WILLIAM B. TUNSTALL.
